STENCIL PRINTING APPARATUS

Harmon P. Elliott, Watertown, Mass., assignor to
The Elliott Addressing Machine Company, a
corporation of Massachusetts

Application November 10, 1933, Serial No. 697,407

12 Claims. (Cl. 101—48)

This invention relates generally to addressing or other printing apparatus comprising a flat stencil, or more usually, a series of card stencils.

The object of the present invention is the production of a selective stencil printing apparatus of the utmost flexibility in use, in that it may be easily adjusted (1) to print consecutively from each successive stencil fed from the magazine, or, (2) to select certain stencils only and print 5 once from each of such stencils, skipping all others, or (3) to print two or more times from all the stencils fed from the magazine, or (4) to select certain stencils only and print two or more times from each of those, skipping all others, each of 10 such varied methods of operation resulting from a simple readjustment of one or more elements of the entire combination constituting the operating unit. While this apparatus can be used on any kind of an addressing machine, I have herein 15 illustrated it as applied to a novel form of flat pad mechanism, on which an application Ser. No. 5944 for patent on an addressing machine, and which is a continuation in part of the present application, has been filed under date of Feb. 11, 20 25 1935.

The best form of apparatus at present known to me for practicing my invention as above outlined and obtaining the results above recited, is illustrated in the accompanying nine sheets of drawings, in which:

Fig. 1 is a partial plan view of the apparatus, with parts removed and others broken away.

Fig. 2 is a supplemental plan view showing most of the remaining portions of the apparatus 30 with parts broken away and others in section.

Fig. 3 is a partial rear view of the apparatus showing portions of the selective and repeat-printing mechanisms.

Fig. 4 is an end elevation showing the same 40 parts appearing in Fig. 3.

Fig. 5 is a detail cross section on line 5—5 of Fig. 3; and,

Fig. 6 is a detail end elevation taken at the point indicated by the arrow 6 in Fig. 3.

Fig. 7 is a cross section of the essential portions of the printing mechanism taken on line 7—7 of Fig. 8.

Fig. 8 is a front elevation of the same parts.

Fig. 9 is another detail section of the essential 50 parts of the printing mechanism, taken on line 9—9 of Fig. 8, the printing platens being shown separated.

Fig. 10 is a similar view with the platens in closed position, i. e. that of completed contact.

Fig. 11 is a detail section of a portion of the

inking mechanism, taken on line 11—11 of Fig. 7; and,

Fig. 12 is a detail cross section on a larger scale taken on the same plane as that of Fig. 10, but showing the printing platens at the moment of 5 their initial contact.

Fig. 13 shows a cam for triplicate printing.

Throughout the drawings like reference characters refer to like parts.

Referring to Figs. 7, 9, 10, and 11, which illustrate the printing mechanism, the same may be described as follows:

1 is the table of the machine supported in any desired manner, as by legs, one of which is shown at 91. On this table is pivoted at 3 a vibrating 15 frame generally indicated at 2. The pivot shaft 3 is mounted on bracket 4 fastened to the under side of table 1, and projecting up through the opening 21 therein, one of the holding bolts for bracket 4 being shown at 5. A pressure arm 6 is 20 cast on frame 2, and carries at its free end the platen 7 which has a flat face composed of rubber or other elastic composition. 8 is an arm depending from the frame 2 and connected by pivoted link 9 to the swinging member 10 which is 25 pivoted at 11 on the supporting strut 150, also mounted in the bracket 4.

The usual grooved stencil guides along which a series of stencils S are slid into the printing zone between the lower platen 13 and the upper 30 platen 7 are shown at 12, 12. Platen 13 is supported on the free end of the swinging arm 14 pivoted to bracket 4 at 15, and 16 is a roller, the journal of which serves as a pin to connect 13 to 14, and which roller is supported on the cam arm 35 17 which is pivoted at 11, being integral with the arm 10.

The swinging frame 2 has a horizontally extending slot 18 registering with a wider slot 19 in the housing 29 behind it and through which a 40 sheet of paper P or other article on which printing has been done may be fed by means of friction feed wheels 22, operated by mechanism generally indicated at 145 in Fig. 1, which constitutes no part of the present invention. The lower 45 platen 13 is intermittently lifted by cam 17 through the opening 20 in table 1 to meet the descending platen 7, compressing the stencil S and the sheet P to be printed between them.

Ink is supplied to the under surface of platen 50 7 by roller 32 which is mounted in housing 34 pivoted on the lower end of vibrating frame 33 which latter is pivoted at 25, such pivot being supported by arm 23. A frame 24 also swings from pivot 25 and carries a series of ink distribut- 55

ing rolls 28, the lower one of which comes into contact with roller 32 when the matter is moved to the right across the face of the platen 7, and the upper one of which is in contact with the 5 ink carrying drum 26 which is journaled at 27 on the arm 23. Frame 24 has a projecting lug 38 which rests against the adjustable stop screw 31 under the pull of spring 36. Spring 35 anchored on the swinging frame 33 and connected 10 to the free end of pivoted housing 34 holds roll 32 up against the face of the platen 7 during its transit across the same. The vibrating frame 2 has a depending arm 8 which is connected by pivoted link 9 to the swinging member 10, which has 15 a stop lug 135 adapted to engage the stationary strut 150, when the pull of spring 18 anchored on bracket 4 rotates frame 2 in a counterclockwise direction. When, however, the member 10 is swung on pivot 11 in a clockwise direction, it 20 gives a similar swinging motion to frame 2 and forces the upper platen 7 down while the cam 17 engaging roller 16 forces the lower platen 13 upward. When the platen 7 rises on a reverse movement of the apparatus, partly under urge of 25 said spring 18, the adjustable contact screw 39 on slotted connecting rod 41 rises with 41 and strikes the slide block 38 which is pivoted on frame 33 and located in slot 40 in said connecting rod, serving as a guide for the upper end of 41. 30 This gives a clockwise rotation to frame 33 and, when the platen 7 descends again, the spring 37 gives a reverse swinging motion to frame 33, these two motions reciprocating the ink roller 32 across the face of platen 7.

35 As the arm 6 is subjected to great strains in this operation, which are transmitted to the skeleton casting forming a part of frame 2, I provide the additional bearing rollers 43 for frame 2, carried in the overhead housing 44, to take up 40 some of these strains. 45 is a cover for the inking mechanism pivoted at 49 on the housing 48 and having a stop lug 46 which rests against the projecting end of arm 23. A distributing roll and an ink fountain shown at 47 together constitute 45 a source of ink supply of the usual type as best shown in Fig. 7, depositing such ink on the cylindrical surface of drum 26.

The mechanism for controlling the operation of the printing platens 7 and 13 is substantially the 50 same as that illustrated and described in my co-pending application Ser. No. 704,440, filed December 29, 1933, and in Patent No. 1,183,385 granted to Sterling Elliott, April 23, 1916, as further modified and improved in the form shown 55 in my Patent No. 1,883,643, granted October 18, 1932. The prime moving mechanism comprises the hereinbefore mentioned swinging cam plate 53 pivoted at 11 and oscillated by pitman 51 from a motor, not shown. 52 is a latch pivoted on 60 swinging member 10 at 53 and carrying a lug 146 which is adapted to engage the notch 164 in the cam plate 50, then locking the swinging member 10 to the oscillating cam plate 53 and causing reciprocation of the printing platens, as before described.

65 The cam slot 54 in plate 50 also cooperates with the rounded head 55 on one arm of the belt crank 56 which is carried on the vertical pivot 57 and which operates the stencil feed mechanism hereinafter described.

The latch 52 is normally urged toward engagement with notch 54 by means of spring 152 anchored at 151, and its movement in that direction is limited by pin 95 carried by it striking the 75 stop 96 on the end of member 10. The movements

and successive positions of the latch 52 are mainly controlled by the swinging trip-arm 59 which bears against the anti-friction roller 58 carried on the end of the latch. This trip-arm is mounted on shaft 60 and has two upwardly extending branches, one of which carries anti-friction roller 140 cooperating with cam 139 on plate 50, to give the arm 59 a counterclockwise rotation when the cam plate 50 rises. This movement takes place against the resistance of spring 62. An 10 other upwardly extending arm 63 integral with 59 cooperates with the latch 64 loosely carried by shaft 66. Latch 64 extends through an opening in 63, and, when its latch projection 65 engages the right hand surface of 63, it holds the 15 arm 59 in contact with roller 58 and so forces the latch 52 out of engagement as shown in Fig. 4, with the result that the cam plate 50, when then rising and falling, operates the stencil feed mechanism only, and not the printing mechanism. 20 Shaft 60 is supported from bracket 61.

If the latch 64 is held up so that the arms 63 and 59 are free to swing, the latter will be held during the greater portion of each cycle of operations away from latch roller 58 by spring 62 and 25 the member 10 will be locked to cam plate 50 because spring 152 has pulled latch 52 into engagement with notch 164 in said cam plate 50. This will produce a printing operation during each 30 cycle of operations and, if the stencils are fed continuously, there will be one printing operation performed with each. If, however, the printing operation is interrupted while the stencil feeding continues, certain of the stencils will be skipped, that is, will go through without being 35 printed. Latch 64 may be thus held up by either one of two mechanisms, as follows: Referring to Figs. 2 and 3, cam disk 70 is there shown journaled at 71 in housing 78 and cooperates with the cam nose 69 on the free end of 40 latch 64. A ratchet wheel 74 is rigidly connected to cam 70 by the intervening notched locking-disk 137, and all three are turned as a unit tooth by tooth by the pawl 73 carried by pawl lever 72 also journaled on pin 71 and oscillated by slotted 45 pitman 75, to which 72 is pivotally connected. A crank arm 76 is rigidly mounted on the pivot pin 53 of latch 52 so as to swing with said latch and carries a pin 77 which slides in the slot shown in pitman 75, said slot being of such length that 50 the pin 77 will strike its upper end slightly before the completion of the upward movement of member 10, if latch 52 is in engagement, thereby 55 vibrating pawl lever 72. A spring locking pawl 138 bears on the locking disk 137, and the parts 60 are so proportioned that by each operation of the ratchet mechanism the cam 70 will be moved far enough to shift the registration of the cam and nose 69 from low to high or vice versa. Consequently the latch 64 is allowed to drop into engagement with the arm 63, by one cycle of operations and lifted out of engagement at the next, if latch 52 is in engagement with notch 164, otherwise the pawl 73 is not operated and cam disk 70 remains at rest. Similarly the printing 65 operation may be controlled by a selector apparatus of the general character described in my above noted co-pending application, comprising a frame 147 mounted on a vertical slide 148 and carrying one or more contact pins 149 which may 70 or may not register with certain holes punched in the frame of each stencil S as such stencil comes under frame 147 and pins 149 are lowered into contact with the stencil. The slide 148 is raised and lowered by the oscillation of the 75

crank 267 which is fast on shaft 266 (see Fig. 4), and is connected by link 68 to crank 67 fast on shaft 66. Shaft 66 carries a dependent crank arm 126, on the free end of which is journaled the 5 anti-friction roller 125 which cooperates with the cam 127 carried by the cam plate 50, so that the above described linkage is oscillated once during the latter part of each upward motion of the cam plate 50. An electric circuit is provided, one terminal of which, shown at 153 in Fig. 1, is connected to the mechanism carrying and operating pins 149, all of which mechanism is insulated from the main frame of the machine including the stencil guides 12. If, therefore, 10 the pin or pins 149 all pass through perforations in the frame of certain stencils, they will come in contact with the guides 12 and establish a circuit which includes the magnet 82 which, when energized, vibrates the armature lever 80 pivoted at 81, the other arm of said lever extending under latch 64, as best shown in Fig. 3. This lifts the latch free from arm 63 so that spring 62 can pull arm 59 away from roller 58, and permit latch 52 to engage cam plate 50, so that on the next cycle 15 of operations, when that particular stencil has been fed into the printing zone, the platens 7 and 13 will grasp the stencil and any sheet to be printed between them. 122 is a laterally projecting lug on depending arm 126 to which spring 123 is connected so as to normally hold roller 125 in engagement with cam 127.

The cooperation of these two sets of mechanism produces the following results: The latch nose 69 resting on a depression in cam 70, the arm 35 59 is held against roller 58 and latch 52 is held out of engagement with cam plate 50, and no printing occurs, the stencils being skipped until one comes under the frame 147 having holes registering with pins 149, whereupon magnet 82 40 is energized and latch 64 is lifted, thus allowing latch 52 to engage so as to cause printing during the next cycle. The consequent raising of pin 71, resulting from the inwardly swung position of latch 52 and the upwardly swung position of crank arm 76 causes a lifting of pitman 75 and pawl 73 is actuated to rotate cam 70 and bring a high portion thereof under latch nose 69, thus continuing to hold up latch 64 and thereby leaving arm 59 free to be pulled to the left by spring 45 12, permitting latch 52 to remain in engagement during another cycle and print again from the same stencil. At the next cycle, however, a low portion of cam 70 is turned under latch nose 69, latch 64 again engages 63, and printing is 50 stopped until another stencil with the same arrangement of holes comes along.

The stencils are fed along the grooved guides 12, 12 by means of a reciprocating slide 89 moving in and out under the stencil magazine 88 (best 55 shown in Fig. 2), said slide having a projecting toe 99 on which the rear end of the bottom stencil in the magazine will rest while the slide 89 forces it out along the guides 12 to the left under the pull of the slotted connecting rod 83, if the 60 pin 87, carried by the slide 89, is in engagement with the offset portion 85 of the L-slot 84, 85, in connecting rod 83. The other end of 83 is pivoted to one arm of the bell-crank 56 which is directly operated and actuated by the engagement of head 55 with the cam slot 54 in cam plate 50. If the offset portion 85 of the slot is not in engagement with pin 87 the other portion 65 84 of the slot will permit connecting rod 83 to reciprocate idly on pin 87 and the stencil then in 70 the printing zone will remain there, so that if the 75

platens 7 and 13 are then actuated the repeat printing above described can be done.

83 is normally held in position to produce reciprocation of the slide by spring 101, but can be forced into the position shown in Fig. 2 by co-operation of the friction rollers 100, 100 carried on the free end of swinging member 97 pivoted at 98 on an extension 104 from plate 144 which is fastened to the under side of table 1. Member 97 is so swung intermittently, when desired, by 10 cam disk 112, which is journaled on pin 103 set in housing 132, also carried by plate 144. On pin 103 are also mounted a ratchet disk 105 and a locking disk 119, on which latter bears the spring locking pawl 120 mounted on plate 144. A pawl 15 106 carried by a swinging lever 107 cooperates with ratchet disk 105 to turn both cam disks 102 and 112, with a step by step movement, whenever 107 is oscillated by reason of the fact that the pin 108, carried by its free end, engages the 20 offset portion of the L-slot 109 in the flat connecting rod 110, the other end of which is pivoted to the bell-crank 56.

Referring more particularly to Figs. 2, 3, 4, and 5, two oppositely extending crank arms 116 and 136 are shown pinned on shaft 60. The upper one, 116, is pivoted at its free end to a slide bar 115, moving on idling roll 131 between guides 121, and carrying on its free end anti-friction roll 114 which bears on connecting rod 110. When the 30 arm 63 is released by latch 64 to produce a printing operation shaft 60 is allowed to turn slightly in a clockwise direction (looking at Figs. 4 and 5) and arm 116 then moves in the same direction so that roll 114 pulls 110 away from pawl lever 107 35 (see Fig. 2) against the resistance of springs 127, so that the notch in L-slot 109 engages pin 108, and at the next vibration of bell-crank 56 pawl 106 and ratchet disk 105 rotate lower cam disk 112 far enough to swing an elevation of such cam 40 disk against the adjacent friction roller 100. This swings frame 97 toward connecting rod 83 against the tension of spring 101 and holds the longitudinal portion 84 of the slot in said connecting rod in line with pin 87 on stencil feeding slide 89. 45 Consequently the rod 83 then reciprocates idly and the line of stencils in guides 12, 12 do not move, the one in the printing zone staying there for the second, or duplicate, printing operation. During such second printing, however, cam disk 50 112 is again turned so that the roll 100 bearing on it drops into a depression under the urge of spring 101, and upon the succeeding operation the notch 85 in the connecting rod slot engages pin 87, and thereafter the feeding of stencils is resumed but 55 no printing occurs if the next stencil to come under frame 147 does not have the combination of holes punched in it which have been punched in all stencils which are to be used in printing. This results because the magnet 82 is then not 60 energized, latch 64 is left down, and arms 63, and 59 are held in position to disengage latch 52, for skipping such stencil and all succeeding stencils of the same character. The resultant position 65 of shaft 60 also moves roll 114 away from connecting rod 110 and spring 127 pulls it over so that the notch in slot 109 is disengaged from pin 108 and the pawl 106 is no longer vibrated to turn cam disk 112 further, but leaves it with a low point against roll 100, so that the feeding of stencils continues until arm 63 is released by the co-action of another selected stencil and pins 149, another printing operation is initiated, and the stencil feed slide 69 is again disabled for one cycle 70 75

to again permit the duplicate printing therefrom above described.

While the apparatus shown and described produces duplicate printing, a mere substitution for 5 cam disks 70, 102, and 112 of similar disks having high portions of double width, such as disk 170, shown in Fig. 13, would produce triplicate printing, and sets of cams having crowns of still greater widths would increase the number of 10 printings to any desired extent.

Upper cam disk 102 turns with 112 and, as a result, when the parts are in position shown in Fig. 2 and the stencil feed is temporarily disabled to permit duplicate printing, the roll 190 15 journaled on twisted connecting rod 111 is left on a high point of cam disk 102, and, such twisted connecting-rod 111 pivoted at its free end to crank 113 on shaft 66, holds the selector frame 147 in raised position. This returns roller 125 20 on depending arm 126 out of contact with cam 127 in spite of the pull of spring 123. The other end of 111 is guided by pin 103 which engages slot 90 on that end portion of 111.

Pawl 73 is fast on its pivot-pin 172 which carries 25 an eccentrically located pin 94 (Figs. 3 and 6) which is connected by spring 93 with an anchorage pin 92 on pawl lever 72. This spring can be swung to either side of the axis of pin 172 with a snap-over action, serving in one position to hold 30 the pawl in engagement with ratchet disk 74, and in the other position to hold the pawl out of such engagement. Similar adjustments of pawl 106 are rendered possible by snap-over spring 130 anchored at one end to pin 229 on pawl lever 167, 35 and at the other end to pin 129 set eccentrically in pawl pivot pin 128. The movement of pawl lever 72 is limited by its stop pin 163 engaging one or the other end of notch 164 cut in journal 71, as shown in Fig. 6.

40 The shaft 60 may be manually oscillated by link 118 connected at its upper end to crank arm 136, and at its lower end to a skip pedal (not shown).

While I have hereinbefore described the platen 45 broadly as carried by arm 6, I prefer to employ a special mounting for it shown more in detail in Figs. 10 and 11, where the rubber pad is cemented to a plate 165 slidable in undercut grooves 157 in housing plate 156 which is hinged on pin 169 50 set in sub-frame 159 carried by arm 6. Plate 165 can be pulled out by grasping pin 172, and plate 156 can be given slight swinging adjustments on its hinge pin 169 by turning pressure screw 158 and holding screw 161. The inking roll 32 has 55 anti-friction rollers 155 journaled on sub-frame 34 and running on track rails 154 fast on plate 156.

The detail view, Fig. 6, of the ratchet-mechanism-operating cam-disk 70, shows a stop pin 163 60 carried on the boss of the pawl lever 72 and moving in the wide, shallow notch 162 cut in a cap plate 166 which is held on the end of the journal pin 71 of the cam and is prevented from rotating by the dowel pin 157. This limits the counterclockwise rotation of pawl lever 72 and holds up the slotted pitman 75 after the downward movement of the latch 52 has lowered pin 71 away from the upper end of the long slot in said pitman.

70 The various methods of operation of the above described apparatus may be concisely explained as follows:

If both pawls 73 and 106 are swung back out of operative position all the cam mechanisms will 75 be disabled, and if the cam disk 70 is then so

turned that a high point will come under the nose 69 of the latch 64, the selector mechanism will also be disabled, and when the machine is started up it will operate as a standard addressing apparatus after the manner of the mechanism described in the before mentioned patent to Sterling Elliott No. 1,189,385, by printing once for each stencil fed out of the magazine.

Again, if both pawls are turned back from operative position but cam disk 70 is turned so that 10 the nose 69 of latch 64 rests on a low point, the selector mechanism will become operative and, when the machine is started, it will skip all stencils except those having the predetermined arrangement of holes, but will print only once from 15 each of such stencils, functioning as a straight selective addressing machine after the manner of the apparatus described in my hereinbefore noted co-pending application Serial No. 704,440.

If, however, pawl 73 alone is turned back out 20 of operative position and cam 70 is turned so that a high point comes under the latch nose 69, while pawl 106 is left in operative position, the selector apparatus will again be disabled so that there will be printing at every operation of the machine, 25 all the stencils being used. But inasmuch as the continual movement of the arm 59 into the position permitting engagement of the latch 52 for effecting printing operates to pull the connecting rod 118 away from ratchet disk 105 so that the 30 pin 168 on the ratchet lever 107 is continually engaging the offset notch in the L-shaped slots 109 in said connecting rod, this ratchet 105 is continuously operated, thereby rotating, during each cycle, the lower cam disk 112 a distance of 35 half a tooth, so that the stencil feeding slide connecting rod 83 is disabled after every other cycle, thereby disabling the stencil feed apparatus and leaving each stencil in the printing zone for a repetition of the printing operation therewith. 40 As a result every name and address will be printed twice.

Finally, if both pawls 73 and 106 are left in operative position, as previously described and shown in the drawings, the apparatus will automatically operate in the manner heretofore explained in detail, and duplicate printing with each selected stencil will be performed, while all others will be skipped.

The use of the upper cam disk 102 and the 50 twisted connecting rod 111 actuated thereby to disable the selector apparatus whenever duplicate printing is being done is not absolutely necessary, as the second lowering of the pins 149 for a second engagement with the stencil in selective position, while the second printing is being done with the stencil ahead of it in the printing zone, does not interfere with the desired operation of the mechanism. The disabling of the selector mechanism at this time, however, saves a certain 60 amount of wear on the apparatus and drain on the batteries supplying current to the selector circuit, and also diminishes the possibilities of the occurrence of sparking at the contacts. I am aware, of course, that in the construction of addressing mechanisms comprising an ink-applying mechanism operating in a printing zone to which a series of legend-bearing elements, either card stencils or type bearing plates, are fed in succession for cooperation in the printing operation, 65 means have heretofore been provided for skipping some of such stencils or plates, either by manual control or by the actuation of an automatic selector mechanism, or for repeat printing from some or all of such legend-bearing elements 70 75

under manual control, but the present invention is believed to embody the first successful attempt to produce a machine which will run continuously and do one or another or several of these things 5 automatically whenever first manually adjusted for the particular purpose selected by the operator.

The particular method of operation of the swinging platens which produces the progressive 10 increase of the area of contact between them and the stencil and paper, which renders the flat pad printing with stencils possible and constitutes an important feature of my invention, 15 (not herein claimed) is illustrated in somewhat exaggerated form in Fig. 12. This result is attained in two ways; which are cumulative in the apparatus here shown.

Evidently, if the two platens were swung from the same hinge axis, or from two axes both of 20 which lay in the plane of contact of the two platens, and the slight thickness of the film of ink on one platen were disregarded, the two platen surfaces would come into complete contact throughout their opposing areas at the instant 25 that both, or the latest one to arrive, came into such plane of contact, and the same difficulty with the trapping of air bubbles would occur substantially as though one platen were stationary and the other one was forced down on it by a 30 plunger traveling on a line at right angles to the surface planes of the two platens.

This result I avoid according to my invention by using an elastic surfacing material (such as shown at 7) for at least one of the pads, and 35 then so adjusting the parts that the common plane of contact is parallel to the surface of the elastic platen only when that elastic material has been compressed by contact pressure to the extent desired for satisfactory printing. As a 40 result, when the platens are approaching one another and the initial contact occurs, they are (due to the swinging motion of one or both) in relative positions such that their surface planes are slightly inclined one to another and the 45 initial contact then occurs only along the mathematical line at one edge of at least one platen surface, and from there extends progressively to the other edge as the movement of compression of the elastic material forming platen 7 is completed.

Furthermore, I exaggerate the above action to a certain extent, and also produce a slight wiping action of one platen on the other, by separating their respective hinge axes 3 and 15 (see Fig. 55 9) in a direction substantially at right angles to their common plane of ultimate completed contact. It will be seen on looking at Fig. 9 that as the platen 13 rises toward the stencil S (which must be in the plane of final contact between 13 and 7) not only will the lefthand edge of platen 13 touch the stencil before the rest of its surface comes into contact after the completion of such contact, but during the completion of its upward movement there is a slight component of 60 horizontal movement of said platen to the left due to the axis 15 about which it is pivoting being considerably below the plane of stencil S. This slight wiping motion of the platen 13 also tends to squeeze out and wipe away the air bubbles 65 by dragging them to the left, as distinguished from being slapped up on them simultaneously at all points, as would be the result if the platen 13 were being lifted up on a vertical plunger.

The particular advantage of having the operative portion of the upper platen 7 removable in

the manner hereinabove described is that rubber platen facing sheets 7 of different areas can be substituted from time to time as the area on which printing is to be done is to be changed. Also it is possible to have a certain portion of the 5 area of any platen cut out, and when such a one is inserted into operative position in the undercut guideways 157 (see Fig. 11) only a portion of the matter cut in each stencil being run through the machine will then be printed. Thus, 10 if it were desired to make up a list of all the names, omitting the addresses, it would not be necessary to make up a whole new set of stencils, but the addressing stencils could be used with a rubber pad 7 which had been cut away so that 15 only the line of the stencil which prints the name would come into use at each operation.

Having described my invention, I claim:

1. In a stencil printing apparatus comprising a swinging ink-carrying platen, a series of card 20 stencils, means for swinging said platen into, and out of, contact with any stencil then in the printing zone, and mechanism for feeding said stencils one by one into said zone, together with a device for causing said platen to effect printing operations only when selected stencils come into said zone, the combination, with said above described apparatus, of mechanism manually adjustable so as to produce repeat printing with each of such selected stencils automatically while in such 30 adjusted condition.

2. An apparatus such as defined in claim 1 combined with additional mechanism manually adjustable so as to disable said selective device during each such repeat printing operation automatically while in such adjusted position.

3. A combination such as defined in claim 1 in which said platen swinging means is controlled jointly by said selective device and by a constituent element of said platen swinging means, 40 whereby, whenever said selective device initiates a printing operation, said last mentioned element will automatically repeat it.

4. A combination such as defined in claim 1 in which said automatic mechanism for producing 45 repeat printing includes a cam disk which may control said selective device, and a pawl and ratchet mechanism for rotating said cam disk.

5. A combination such as defined in claim 1 in which said adjustable mechanism for producing 50 repeat printing includes a cam disk which may control said selective device, and a pawl and ratchet mechanism for rotating said cam disk, said pawl being temporarily adjustable at will into an inoperative position; whereby said cam 55 may be left at rest while other portions of the entire machine continue in operation.

6. A combination such as defined in claim 1 in which said adjustable mechanism for producing 60 repeat printing comprises means for temporarily disabling said stencil feeding mechanism; whereby the stencil then in the printing zone is permitted to remain there for such repeated printing operation.

7. A combination such as defined in claim 1 65 in which said adjustable mechanism for producing repeat printing comprises means for temporarily disabling said stencil feeding mechanism; whereby the stencil then in the printing 70 zone is permitted to remain there for such repeated printing operation, said last mentioned means comprising a continuously reciprocating member, a stencil feeding slide, a connecting-rod permanently pivoted to said member but detach- 75

- ably connected to said slide, and a means adapted to make or break said connection.
8. A combination such as defined in claim 1 in which said adjustable mechanism for producing repeat printing comprises means for temporarily disabling said stencil feeding mechanism; whereby the stencil then in the printing zone is permitted to remain there for such repeated printing operation, said last mentioned means comprising a continuously reciprocating member, a stencil feeding slide, a connecting-rod permanently pivoted to said member but detachably connected to said slide, and a means adapted to make or break said connection, comprising a cam disk and a pawl and ratchet mechanism for intermittently rotating said disk.
9. A combination such as defined in claim 1 in which said adjustable mechanism for producing repeat printing comprises means for temporarily disabling said stencil feeding mechanism; whereby the stencil then in the printing zone is permitted to remain there for such repeated printing operation, said last mentioned means comprising a continuously reciprocating member, a stencil feeding slide, a connecting-rod permanently pivoted to said member but detachably connected to said slides, and a means adapted to make or break said connection, comprising a cam disk and a pawl and ratchet mechanism for intermittently rotating said disk, said pawl being manually movable temporarily into and out of operative position.
10. A stencil printing machine having a printing zone, a device for successively feeding a se-

ries of legend bearing elements one after the other into said zone, mechanism adapted to cooperate with such element while in said zone to print the legend borne thereby, and means for disabling said mechanism whenever selected members of such series approach said zone, combined with apparatus for causing said mechanism to repeatedly print each of such legends, each said disabling means and said repeat printing apparatus being manually adjustable to inoperative condition; whereby said machine may be adjusted to print from all stencils once, or to repeat printing from all stencils, or to select stencils and print one or more times from each of those.

11. An apparatus such as defined in claim 10 in which each said disabling means and said repeat printing apparatus comprises a pawl and ratchet wheel mechanism in which each pawl is provided with a snap-over spring for holding it in either operative or inoperative positions.

12. An apparatus such as defined in claim 10 in which each said disabling means and said repeat printing apparatus comprises a pawl and ratchet wheel mechanism in which each pawl is provided with a snap-over spring for holding it in either operative or inoperative positions, and also comprises a rotary cam disk moving with its associated ratchet wheel; whereby, after either pawl has been placed in inoperative position, the cam otherwise actuated by it may be manually adjusted so as to cooperate in producing the desired result while at rest.

HARMON P. ELLIOTT.
